7 Claims. (Cl. 19-1)

Our present invention relates to an apparatus for producing a continuous sliver composed of rayon staple fibers from endless rayon filaments.

Many processes and apparatus have been described for solving the problem of producing from continuous artificial filaments an extensible sliver or roving, that is to say the problem of converting the continuous artificial filaments into extensible fiber bundles, without disturbing the original parallelism of the individual fibers during the operation. Frequently, however, difficulties arise in the overlapping of the sections produced by the cutting of the continuous filaments, for these sections must be so distributed in the sliver that

15 a coherent, uniform roving is produced.

It is therefore an object of the invention to provide a new device which permits the cutting of continuous bundles of artificial filaments of any desired thickness, for example bundles 20 weighing 10-20 grams per meter and at the same time drawing the sections in such a manner that a sliver of staple fibers of predetermined length is produced which has good coherence, satisfactory uniformity and good capacity for being 25 drawn.

Reference is made to the accompanying drawings in which—

Figures 1 and 2 show diagrammatically the principle involved in our novel cutting device,

30 Figure 3 is a diagrammatic plan view of the cutting device combined with an intersecting gill-box,

Figure 4 is a diagrammatic cross sectional view of the intersecting gill-box comprising the cutting device according to the invention,

35 Figure 5 shows by way of example means for moving the rotating knife discs upwards or downwards and sideways.

The simplest construction is illustrated in Figure 1, which represents an elevation in the direction in which the band 1 to be cut, shown in cross-section, is travelling. This band, in order to preserve the parallel relationship of the individual fibers and to prepare for the overlapping, 40 must be cut not by a through-cut but by at least two partial cuts alternating from the edges of the band while the band is moving in such a manner that a stepped cutting is produced corresponding with the number of the cutting knives 2. The 45 band during its travel is cut alternately by the knives 2a and 2b, so that the limiting line of each cut is approximately in the direction of the diagonal of the cross-section of a band, as indicated by a broken line in Figure 1. The circular 50 knives may either, as indicated by arrows, oscil-

late on the points 3 or may have a reciprocating movement perpendicular or inclined to the direction of travel of the band. It is also possible to produce the spaced cuts by means of a knife guided in a curved path.

Figure 2 illustrates the same cutting device in a machine for dealing with four bands of fibers. The bands 1a, 1b, 1c, 1d are alternately cut in the manner described by the moving circular knives 2a, 2b, 2c, 2d, 2e the knife 2b which is centrally 10 spaced being so moved as to serve the four bands. The limit of the cut formed by the several knives is indicated by the broken diagonal line in the cross-section of each band.

Instead of the circular knives there may be 15 used a single or double edged band knife which cuts the travelling bands with a partial cut, as described for the circular knives.

In another construction the knife during the cutting operation travels in the direction of the 20 travelling band whereby creasing of the band during the cutting is avoided. Also it is not necessary that the cutting knives serving the band should be parallel to one another; they may be at an angle to each other and to the direction 25 of travel of the band.

Figure 3 illustrates an apparatus in which the 30 cut bands are being further worked. A cutting mechanism comprises the circular knives 2 arranged in an intersecting gill-box. This construction has the advantage that the cut fibers are positively guided by the sets of fallers and that the cut is produced in the fibers while it is in tension owing to the higher speed of the fallers compared with that of the delivery cylinder. 35 The continuous fiber band 1 is delivered to the cutting table by the draught cylinder 4 which precedes the friction roller 5. The band is delivered in the broadest possible form. The cutting table (not shown in the drawings) should 40 have suitably narrow slits through which the knives 2 move to and fro. Preferably, a part of the knife is above and a part below the cutting plane. By controlling the speed of the feed from the delivery cylinder and the lateral movement 45 of the cutting knife, the length of the staple is regulated.

The pieces of band which have been cut by the knives 2 are engaged by the fallers and are 50 successively drawn off by the fallers 7 owing to their higher speed, whereas the parts which are not cut are held back by the pressure of the feed cylinder 4 and by the fallers. A further draught is produced by the drawing cylinder 6.

In Figure 4, which shows the apparatus of Fig. 55

ure 3 in cross-section, *a* is the bundle of continuous filaments, while *b* indicates the continuous sliver produced by cutting and drawing on the gill-box. Identical reference numerals show parts corresponding with Figure 3. The means providing a to-and-fro-movement of the rotary cutting discs *2a* and *2b* and which cause the engagement of the knives into and out of the continuous bundle *a* is shown diagrammatically in this figure. Thus, *9* represents driving means, for instance electric motors, which by means of the roller *3* and the belt *10* cause rotation of knives *2a* and *2b*.

The push rod *11* causes the reciprocating lateral movement of the cutters, while the means for producing up and down movement thereof are not shown in this figure.

In Figure 5, *9* is a motor with driving belt *10*, which is led over roller *3* and rotates the cutter *2a*. The curved disc *13* by means of the push rods *11* and *15* which latter engages the periphery thereof with its end piece *16* and is pivoted on the shaft of the motor *9* controls the up and down movement of the knife *2a*. The rotary eccentric disc *14* causes the push rod *12*, mounted on the disc by its slotted end piece *19* and secured to push rod *11* at the joint *20* to perform a to-and-fro-movement in the direction of the arrows. The roll *17* runs on the periphery of disc *14*, which rotates around the turning point *18*.

By these means the center of the knife *2a* is caused to move along a path defined by the curve *21*.

Other means to perform the double reciprocating movement will readily suggest themselves to those skilled in the art. While we have explained the nature of our invention with reference to the specific embodiments set forth in the drawings, we do not wish to limit ourselves to this specific embodiment.

A further possibility for the arrangement of the cutting device is that the cutter is not arranged between the feed cylinder *4* and the friction roller *5* but within the intersecting gill-box. In this case the rotating knives are so guided by mounting their axes in grooves that they can move with the needle rods in the direction of the band. The shafts must then be arranged to be movable in the vertical direction so that when the cutting operation is complete they may be removed from the gill-box and brought into the initial position.

It is also possible in the arrangement first described to arrange the knife not, as indicated in Figure 1, perpendicularly to the direction of travel of the band but at a certain angle obliquely thereto, so that the axes of two co-operating knives can be parallel or at a certain angle to each other.

We claim:

1. A cutting device for converting a bundle of continuous filaments into an extensible sliver composed of staple fibers in substantially parallel alignment, comprising in combination, at least two rotary cutting blades alternately engaging said bundle of continuous filaments, driving means for rotating said blades, and means for imparting to said blades a double reciprocating movement in lateral and vertical direction, one of said rotating cutting blades cutting only one portion of said bundle and another blade cutting another portion, each partial cut being spaced from the other by a predetermined distance longitudinally of the filament bundle.

2. A cutting device for converting a bundle of continuous filaments into an extensible sliver composed of staple fibers in substantially parallel alignment, comprising in combination, at least two rotary cutting blades alternately engaging said bundle of continuous filaments, driving means for rotating said blades, and means for imparting to said blades a double reciprocating movement in lateral and vertical direction, means for feeding the bundle of continuous filaments to said cutting blades and means for withdrawing the sliver of cut filaments from the cutting area, one of said rotating cutting blades cutting only one portion of said bundle and another blade cutting another portion, each partial cut being spaced from the other by a distance longitudinally of the filament bundle controlled by the speed of said feeding means.

3. A cutting device for converting several bundles of continuous filaments into extensible slivers composed of staple fibers in substantially parallel alignment comprising in combination five rotary cutting blades, two of said blades alternately engaging a bundle of continuous filaments, driving means for rotating said blades, and means for imparting to said blades a double reciprocating movement in lateral and vertical direction, one of said rotating cutting blades cutting only one portion of said bundle and the next blades cutting another portion, each partial cut being spaced from the other by a predetermined distance longitudinally of the filament bundle.

4. A cutting device for converting a bundle of continuous filaments into an extensible sliver composed of staple fibers in substantially parallel alignment comprising in combination, at least two rotary cutting blades alternately engaging said bundle of continuous filaments arranged in different planes, driving means for rotating said blades, and means for imparting to said blades a double reciprocating movement in lateral and vertical direction, one of said rotating cutting blades cutting only one portion of said bundle and another blade cutting another portion, each partial cut being spaced from the other by a predetermined distance longitudinally of the filament bundle.

5. A cutting device for converting a bundle of continuous filaments into an extensible sliver composed of staple fibers in substantially parallel alignment, comprising in combination two rotary cutting blades alternately engaging said bundle of continuous filaments arranged in front of an intersecting gill-box, two electric motors imparting rotary movement to said blades, means comprising a curved disc and a push rod arrangement connected with the center of each of said blades, said means imparting to said blade a reciprocating lateral movement, means comprising an eccentric disc and a push rod arrangement connecting said disc with the center of each of said blades, said last named means imparting to said disc a reciprocating vertical movement, a series of rollers for feeding said bundle of continuous filaments to said blades, and a series of rollers for withdrawing the cut fibers from said blades, the lateral and vertical movement of said blades being so adjusted that one half of the bundle of continuous filaments is cut by one of said blades, the other half being cut by the other blade, said last named cut being spaced from said first cut by a distance controlled by the speed of the feeding rollers.

6. A cutting device for converting several

bundles of continuous filaments into extensible slivers composed of staple fibers in substantially parallel alignment comprising in combination a number of rotary cutting blades, said number 5 exceeding the number of bundles of filaments by one, driving means for rotating said blades, means for imparting to said blades a double reciprocating movement in lateral and vertical directions, means for guiding each bundle of filaments between and in a direction substantially perpendicular to a pair of adjacent blades, whereby each 10 bundle of filaments is alternately brought into engagement with one blade of said pair, one of said blades cutting only one portion of one bundle and the other blade cutting the other portion of said bundle, each partial cut on any one bundle of fibers being spaced from the other by a predetermined distance longitudinally of said filament bundle.

20 7. A cutting device for converting four bundles

of continuous filaments into extensible slivers composed of staple fibers in substantially parallel alignment comprising in combination five rotary cutting blades, driving means for rotating said blades, means for imparting to said blades a 5 double reciprocating movement in lateral and vertical directions, means for guiding each bundle of filaments between and in a direction substantially perpendicular to a pair of adjacent blades, whereby each bundle of filaments is alternately brought into engagement with one blade of said pair, one of said blades cutting only one portion of one bundle and the other blade cutting the other portion of said bundle, each partial cut on any one bundle of fibers being spaced 10 from the other by a predetermined distance longitudinally of said filament bundle.
